ELECTRONIC IMPULSE GENERATOR

Carl F. Rench, Troy, Ohio, assignor to The National Cash Register Company, Dayton, Ohio, a corporation of Maryland

Original application December 17, 1949, Serial No. 133,540, now Patent No. 2,591,007, dated April 1, 1952. Divided and this application March 14, 1951, Serial No. 215,483

12 Claims. (Cl. 340—345)

1

This invention relates to a novel impulse generating apparatus and is a division of application Serial No. 133,540, which was filed on December 17, 1949, and which issued on April 1, 1952, as Patent No. 2,591,007.

The novel impulse generator is of a type which is capable of effecting entries simultaneously in a plurality of denominational orders of an accumulator. The impulse generator utilizes a plurality of tubes, which are common to a plurality of denominational orders, for producing impulse trains corresponding to the digits "1" to "9" and containing corresponding numbers of impulses. These impulse trains, which are available to the plurality of denominational orders, may be selectively switched to any one or more denominational output conductors of the impulse generator by corresponding denominational digit-selecting means.

The plurality of tubes of the impulse generator includes an oscillator-controlled means for producing driving impulses, a chain of tubes containing a "start" tube and a priming tube for each of the digits "1" to "9," an impulse-train-producing tube for each of the priming tubes and a transfer-effecting impulse-generating tube.

The priming tubes are driven by the driving impulses, once the "start" tube has been rendered conducting, and will become conducting one after another in sequence, beginning with the "9" tube and ending with the "1" tube. As each priming tube becomes conducting, it conditions a related impulse-train-producing tube also to respond to the driving impulses and produce an impulse train containing the number of impulses corresponding to the value of the priming tube. As soon as the impulse trains have been produced, the "start" tube and the priming tubes are returned to their non-conducting status and made ready for another amount-entering operation.

The impulse-train-tube circuit provides a low impedance source for the impulses which is capable of producing extremely strong impulses, so that their quality will not be impaired and they will be able to produce satisfactory operation of the accumulator even though the impulses are switched simultaneously to a plurality of denominational output conductors to cause entries to be made in corresponding orders of the accumulator. This circuit also minimizes cross-talk or interference effects between conductors forming the output circuits.

The oscillator of the impulse generator is also used to control a further impulse-generating means to provide tens-transfer-effecting im-

2

pulses for causing tens transfer entries to be made in an accumulator, when required, and in such a manner as not to interfere with the normal digital entries in the accumulator.

It is an object of this invention to provide an impulse generating apparatus which is capable of producing output impulses simultaneously on a plurality of output conductors and which requires but a minimum of components.

10 A further object of the invention is to provide a low impedance source of impulses which can produce strong impulses whose quality will not be impaired when they are switched simultaneously to a plurality of denominational output conductors.

15 With these and incidental objects in view, the invention includes certain novel features of construction and combinations of parts, a preferred form or embodiment of which is hereinafter described with reference to the drawings which accompany and form a part of this specification.

20 Of the drawings:
Figs. 1-A and 1-B together show a circuit diagram of an impulse generator and the controls therefor.

25 In order that the invention may be explained more fully, a preferred embodiment of the invention will be described, in which description values of potential and circuit elements, such as resistors and capacitors, will be given and types of tubes will be specified. It is not intended, however, to limit the invention to the embodiment described nor to limit the circuit values and tube types to those specified, because these are merely selected as illustrative. It is obvious that other potentials and/or other similar tube types can be used and the circuit values of resistance and capacitance can be adjusted to maintain the proper relation between the various parts of the circuits. Throughout the circuit diagrams, the heater elements for the tubes are shown conventionally.

Impulse generator

45 The impulse generator is capable of generating impulse trains containing different numbers of impulses corresponding to the digits of the notation in which computations are to be made, and is capable of sending the required number of impulses over one or more output conductors according to the digits desired to be entered into various denominations of an accumulator. The impulse generator and its controls are shown in Figs. 1-A and 1-B.

50 55 A multi-vibrator type oscillator consisting of

tubes 11 and 12 (Fig. 1-A) is provided to drive the impulse generator and to coordinate the operation of the tens transfer means of the accumulator with the digit entries. These tubes have their anodes 13 and 14 connected over points 15 and 16 and resistors 17 and 18, of 22,000 ohms each, to conductor 19, which extends to terminal 29, to which a potential of +250 volts is applied. The cathodes 21 and 22 of these tubes are grounded. The grid 23 of tube 11 is coupled over capacitor 24, of 50 micro-microfarads, to point 16 in the anode circuit of tube 12 and also is connected to ground over a 1-megohm resistor 25. Similarly, grid 26 of tube 12 is coupled over capacitor 27, of 50 micro-microfarads, to point 15 in the anode circuit of tube 11 and also is connected to ground over resistor 28 of 1 megohm. While tubes 11 and 12 are shown and function, as two separate tubes, they need not be separate but can be the two sections of a single tube such as may be purchased from Radio Corporation of America under type designation 12AU7. With the values given, and using the 12AU7 type of tube, the oscillator will oscillate at about 7,500 cycles per second, and points as 15 and 16 will make a like number of positive potential excursions.

Point 16 is coupled over a capacitor 30 of 250 micro-microfarads to grid 31 of a driving impulse generating tube 32. Tube 32, which is shown as a separate tube but which preferably is a half of a twin triode, such as a tube sold by Western Electric Company under the type designation 2C51, is normally biased to cut-off by having its grid 31 connected over a resistor 33 of 150,000 ohms and over conductors 34 and 35 to terminal 36, to which -30 volts is applied, and is allowed to conduct momentarily each time the potential of point 16 becomes sufficiently positive in the operation of the oscillator to overcome the negative bias on the grid 31.

Tube 32 has its anode 37 directly connected to the conductor 19, to which +250 volts is applied, and has its cathode 38 connected to ground by a relatively low impedance circuit including point 39 and resistor 40 of 4,700 ohms.

With the values given, a positive potential impulse will be produced at point 39 each time tube 32 conducts momentarily, and these impulses are used to cause the sequential operation of a chain of priming tubes and to drive the impulse-train-producing tubes.

The chain of priming tubes (Figs. 1-A and 1-B) utilizes gaseous tetrodes, such as tubes sold by General Electric Company under type designation GL5663, and includes a "start" tube and a priming tube for each of the digits "1" through "9."

The "start" tube (Fig. 1-A) has its anode 45 connected directly to an anode potential supply conductor 46, which normally has a potential of +125 volts supplied thereto from point 47 in the cathode circuit of an extinguishing tube 48.

The control grid 49 of the "start" tube is normally biased to prevent conduction in the tube by being connected over resistor 50, of 47,000 ohms, point 51, and resistor 52 of 1 megohm to terminal 53, to which a potential of -30 volts is applied.

The cathode 60 of the "start" tube is given a potential slightly more negative than ground when the tube is non-conducting. This potential is obtained by connecting the cathode at point 61 in a resistance-capacitance network extending from point 62 on conductor 63, to which a

potential of -108 volts is applied at terminal 64, over resistor 65 of 1.8 megohms, point 66, resistor 67 of 1.6 megohms, point 68, resistor 69 of 15,000 ohms, point 61, and resistor 70 of 22,000 ohms to ground. Point 68 in this circuit is coupled to ground over a capacitor 71 of 1,000 micro-microfarads. When conduction occurs in the "start" tube, its cathode 60 will also be conductively coupled to the anode 45, and its potential will change from slightly negative to positive with respect to ground.

The auxiliary or shield grid 72 of the "start" tube is connected to the cathode 60 and will have the same potentials as the cathode.

The "start" tube is the first tube in the chain and is followed by the "9," "8," "7," "6," "5," "4," "3," "2," and "1" priming tubes in that order. The circuits for the various priming tubes are similar and will be clear from an explanation of the circuits for the "9" priming tube (Fig. 1-A).

The anode 75 of the "9" priming tube is connected directly to the anode potential supply conductor 86.

The auxiliary or shield grid 76 of the "9" priming tube is connected over resistor 77 of 47,000 ohms, point 78, and resistor 79, of 1 megohm, to negative potential supply conductor 80, which is connected to terminal 53 and has a potential of -30 volts applied thereto. The auxiliary grid 76 is also coupled over point 78 and capacitor 74 of 10 micro-microfarads to a driving impulse input conductor 73, which connects over point 41 to point 39 in the cathode circuit for tube 32 and receives a positive driving impulse of about 150 volts each time tube 32 conducts momentarily.

The control grid 81 of the "9" priming tube is connected to point 66 in the cathode potential supply circuit for the "start" tube and, with the "start" tube non-conducting, has a normal negative bias sufficient to prevent the "9" priming tube from becoming conducting even though driving impulses are applied to the auxiliary grid. When the "start" tube has been fired and is conducting, the positive potential of its cathode 60 will be reflected on the potential of the control grid 81 of the "9" priming tube and will reduce the negative bias thereon to a point where the tube can become conducting in response to a driving impulse impressed on its auxiliary grid.

The cathode 82 of the "9" priming tube is supplied with potential from a resistance-capacitance network, like the one for the "start" tube, which extends to ground from the negative potential supply conductor 63.

Each of the priming tubes for the digits "8" to "1" inclusive has an anode potential supply circuit and a cathode potential supply circuit like those for the "9" priming tube, each has a negative potential supply circuit for its auxiliary or shield grid and capacitance coupling from its auxiliary grid to the driving impulse input conductor 73, similar to those described above in connection with the "9" priming tube, and each has its control grid connected to the cathode potential supply circuit of the preceding tube in the chain to be primed thereby upon conduction occurring in the preceding tube.

It is to be noted that the driving impulses from tube 32 are not effective to cause an unprimed tube to conduct; consequently the impulses will be ineffective on any of the priming tubes of chain until the "start" tube has been fired and primes the "9" priming tube. The "start" tube 75 is fired in the following manner. Point 51 in

the control grid circuit for the "start" tube is coupled over conductor 85, capacitor 86 of 10 micromicrofarads, and point 87 to the motor bar or start key switch 88, which is normally open but which can be closed to connect point 87 to conductor 89, which extends to terminal 90, to which a potential of +250 volts is applied. When the motor bar or start key switch 88 is closed and the +250 volts is applied to capacitor 86, a positive impulse will be impressed on the control grid 49, which impulse is sufficient to fire the "start" tube, thereby priming or conditioning the "9" priming tube so that it can respond and be fired by the next driving impulse on conductor 13. Point 87 in the motor bar or start key control circuit is connected to ground over resistor 95 of 47,000 ohms to provide a discharge path through which capacitor 86 can be discharged when the motor bar or start key switch 88 is opened.

Each of the priming tubes, when fired, will prime the next tube of the chain, so that it will be fired by the next driving impulse. Accordingly, after the "start" tube has been fired by the closing of the start key switch 88, the next nine driving impulses will fire the tubes of the priming chain one after another.

The tubes of the chain, being gas tubes, will remain conducting, once they are fired, until they are extinguished by the operation of an extinguishing means which includes the tube 48. This operation of the extinguishing means takes place after the last tube in the chain has been fired and has effected its control, at which time all the tubes of the chain are rendered non-conducting.

Since the priming tubes of the chain are fired in sequence by successive driving impulses and are all extinguished at the same time, the several tubes will be conducting for progressively longer periods of time; that is, the "9" priming tube will be conducting longer than the "8" tube, the "8" tube will be conducting longer than the "7" tube, etc.

Each priming tube controls a related impulse-train-producing tube by priming that tube as long as the priming tube is conducting, and enables the driving impulses from tube 32, which are impressed continuously on the impulse-train-producing tubes, to become effective to operate the tube and produce a train of impulses corresponding in number to the digit to which the priming tube is related. For example, the impulse-train-producing tube related to the "9" priming tube will produce a train containing nine impulses, the impulse-train-producing tube which is related to the "8" priming tube will produce a train of eight impulses, etc., the impulse-train-producing tube related to the "1" priming tube producing one impulse.

The circuits and controls for the impulse-train-producing tubes are similar, and it is believed that an understanding of the operation of all these tubes will be clear from a description of the operation of one of them.

The impulse-train-producing tube for producing a train of nine impulses is representative and is shown at 100 in Fig. 1-A. This tube is shown as a separate triode, but preferably it is one half of a twin triode, such as the above-mentioned 2C51 type of tube. The tube has its anode 101 connected directly to conductor 18, which, as explained earlier herein, has a potential of +250 volts applied thereto at terminal 20. The cathode 102 of the tube is con-

nected over point 103 and resistor 104 of 2,200 ohms to point 105 on potential supply conductor 106, which has a potential of +130 volts applied thereto at terminal 107. This anode-cathode potential supply circuit has a very low impedance and will produce a strong positive impulse of about 55 volts at point 103 each time the tube 100 is operated.

Control grid 109 of tube 100 is connected over point 110 and resistor 111 of 100,000 ohms to point 112 in the cathode potential supply circuit for the "9" priming tube. Point 110 in the grid circuit is also coupled over a capacitor 113 of 250 micro-microfarads to the driving impulse input conductor 114, which is connected over point 41 to point 39 in the circuit of the driving impulse generating tube 32. When the "9" priming tube is not conducting, point 112 in its cathode circuit and consequently grid 109 of the impulse-train-producing tube 100 will be slightly negative with respect to ground, and, since the cathode 102 is at a potential of +130 volts, the tube 100 will be biased sufficiently past cut-off that the driving impulses on conductor 114 will be ineffective to cause conduction in tube 100. However, when the "9" priming tube is conducting and its cathode has become positive, point 112 will become more positive and reduce the bias on tube 100 to a point where the driving impulses on conductor 114 will be effective to cause momentary conduction in the tube 100 and thereby provide positive impulses at point 103. Capacitor 115, which is similar to capacitor 11 in the cathode circuit of the "start" tube, delays the application of the priming potential to grid 109 sufficiently that the impulse which fires the "9" priming tube will have passed before the tube 100 is ready for operation. The first driving impulse that will be effective on tube 100 will be the same one that fires the "9" priming tube.

Conductor 120 is connected to point 103 and will have the positive impulses at point 103 impressed thereon. Switch 121, which can be closed by a "9" digit key or any other switch-operating device in the units denominational order, will connect the conductor 120 to a units denominational output conductor 122. Similarly, a switch 123 can be closed by a "9" digit or other switch-operating device in the tens denominational order to connect the conductor 120 to a tens denominational output conductor 124. While only two sets of switches and two denominational output conductors have been shown, it is obvious that as many can be provided as are needed according to the denominational capacity desired.

Each of the other impulse-train-producing tubes has connections similar to the ones given above and is capable of producing the required number of impulses which can be switched to output conductors 122 and 124 as desired. The use of the low impedance source of impulses allows the impulses to be switched to a plurality of output conductors without impairing the ability of the impulses to operate the accumulator.

The driving impulse, which follows the driving impulse which fires the "1" priming tube, will be effective on the primed impulse-train-producing tubes to cause the last impulse in each train to be generated and will be effective on the primed tube 144 (Fig. 1-B) to cause that tube to operate and generate the impulse for effecting an entry of the digit "1" in the accumulator. This impulse which is generated by the tube 144 goes

out over conductor 145, from which it can be switched to output conductors, as 122 and 124. The impulse on conductor 145 also is used to operate the extinguishing means to cause the tubes of the chain to be extinguished and remove the priming from the impulse-train-producing tubes.

As explained earlier herein, the anodes of the "start" tube and the priming tubes "1" to "9" are connected to conductor 46. The potential of conductor 46 is derived from an impedance network having one branch which extends from point 150 on -108-volt conductor 63, over resistor 151 of 56,000 ohms, point 152, and to ground over resistor 153 of 500,000 ohms, and having another branch which extends from point 152, over point 47, to the cathode 154 of the extinguishing tube 48, and through the tube whose anode 155 is directly connected to conductor 89, to which a potential of +250 volts is applied. Tube 48 is preferably of the type sold by Radio Corporation of America under the type designation 6AQ5, and, by varying the impedance thereof, the potential applied to conductor 46 and the anodes of the tubes of the chain can be controlled.

Normally, the potential on the control grid 156 of tube 48 is such that the tube will conduct sufficiently to give its cathode 154 and the conductor 46 a potential of +125 volts. However, when the potential on the grid 156 of tube 48 is modified to increase the impedance of the tube so that less current flows therethrough, the cathode potential and that of conductor 46 will become less positive and even may become negative with respect to ground, thereby causing the anode potential of the conducting tubes of the chain to drop below their cathode potential and the tubes to be extinguished.

The potential of grid 156 is controlled from a resistor 160 in the anode circuit of a twin triode control tube 161, which is preferably of the type sold by Radio Corporation of America under the type designation 12AX7. The anodes 162 and 163 are connected together and over the resistor 160 of 470,000 ohms to conductor 89, to which a potential of +250 volts is applied.

The cathode 164 of one of the triodes of tube 161 is connected directly to terminal 165 and has a potential of +65 volts applied thereto. The cathode 166 of the other triode of tube 161 is connected directly to terminal 167, to which a potential of -98 volts is applied.

Grid 170 cooperates with the anode 163 and the cathode 164 to determine the normal potential applied to grid 156 of tube 48. Grid 170 is supplied with the required potential from an adjustable tap 171 on resistor 153.

Grid 172 cooperates with the anode 162 and the cathode 166 of tube 161 and is effective therethrough to modify the potential of grid 156 of extinguishing tube 48 to increase the impedance of this tube and cause the extinguishing of the tubes of the chain.

The impulse which is generated by tube 144 and is applied to conductor 145 is impressed on grid 172, either directly or through an impulse-widening device, and will cause the extinguishing of the tubes of the chain. In the disclosed embodiment, the impulse on conductor 145 will be applied through an impulse-widening device. Conductor 145 is coupled through a capacitor 175 of .005 microfarad to the anode 176 of a diode 177. Preferably this diode is one half of a twin diode tube of the type sold by Radio Corporation

of America under the type designation 6AL5. Anode 176 of the diode 177 is also connected over resistor 178 of 39,000 ohms and conductor 179 to conductor 63, which has a potential of -108 volts applied thereto. Cathode 180 of the diode is also connected to conductor 179 over a resistor 181 of 1 megohm in parallel with a capacitor 182 of 250 micro-microfarads. Point 183 is this circuit is connected over resistor 184 of 200,000 ohms to the grid 172 of the control tube.

A positive impulse on conductor 145 will be effective, through the low impedance of the diode 177, to charge capacitor 182 and make point 183 and the grid 172 connected thereto more positive. Since the discharge paths for the capacitor 182 are through the resistor 181 of 1 megohm and the high back impedance of the diode 177, the grid 172 will remain positive for a longer time than that required for the impulse on conductor 145.

When grid 172 becomes more positive and more current flows through resistor 160, grid 156 will become more negative and increases the impedance of tube 48, thereby to reduce the anode potential applied to the tubes of the chain sufficiently to cause them to be extinguished.

The impulse-widening means, while not necessary, provides an additional factor of safety in the operation of the device, because it allows the anode potential for the tubes of the chain to be depressed for a longer period of time than required to deionize them and insures that all tubes of the chain will be extinguished.

Accordingly, for each operation of the "start" tube, impulse-train-producing tube 100 will produce a train of nine impulses on conductor 120; tube 130 will produce a train of eight impulses on conductor 131; tube 132 will produce a train of seven impulses on conductor 133; tube 134 will produce a train of six impulses on conductor 135; tube 136 will produce a train of five impulses on conductor 137; tube 138 will produce a train of four impulses on conductor 139; tube 140 will produce a train of three impulses on conductor 141; tube 142 will produce a train of two impulses on conductor 143; and tube 144 will produce an impulse on conductor 145. Each impulse train is common to the plurality of denominational output conductors, and the trains of impulses can be switched to the output conductors according to the digits desired to be entered into the various denominations of the accumulator.

If no entry is to be made in any denominational order of the accumulator, a zero switch, as 146, for that order is closed to connect the related output conductor to conductor 106 over a resistor 147 of 2,200 ohms to provide a comparable low impedance loading for the output conductor when it is not otherwise connected to an impulse-train-producing tube.

It should be noted that the "start" tube and its controls will allow only one impulse-train-producing operation of tubes 100, 130, 132, 134, etc., for each closure of the motor bar or key switch 88, because, as long as the switch remains closed, capacitor 86 will remain charged, and no additional firing impulses can be applied to the control grid 49 of the "start" tube.

The impulse generator also includes a transfer-effecting impulse-generating means which is controlled from the oscillator and is timed to cause transfer entries to be made without interference with digit entries in the accumulator.

The transfer-effecting impulse-generating tube

(190 (Fig. 1-A), which preferably is one half of the above-noted 12AU7 type of tube, has its anode 191 connected over point 192 and resistor 193 of 22,000 ohms to conductor 19, to which is applied a potential of +250 volts, and has its cathode 194 directly connected to ground. Control grid 195 normally biases the tube to cut-off by being connected over resistor 196, point 197, and resistor 198 to conductor 35, to which a potential of -30 volts is applied at terminal 36. Control grid 195 is also coupled from point 197 over capacitor 199 of 250 micro-microfarads to point 15 in the anode circuit of tube 11 of the oscillator, and will allow the tube 190 to conduct each time the potential of point 15 becomes more positive in the operation of the oscillator.

Whenever the tube 190 conducts, a negative potential drop of about 150 volts occurs at point 192 in its anode circuit, and these potential drops are applied over conductor 200 (Figs. 1-A and 1-B) and resistor 201 of 47,000 ohms to the transfer means of the units denominational order of the accumulator and over resistor 202 of 47,000 ohms to the transfer means of the tens denominational order of the accumulator. The transfer means and the manner in which they are operated by the impulses is fully disclosed in said Patent No. 2,591,007, and will not be described herein. The negative impulses which are impressed on conductor 200 will occur during the intervals between the positive impulses on the denominational output conductors 122 and 124 and are effective to cause transfer entries to be made in the accumulator without interfering with the digit entries.

The impulse generating apparatus described above accordingly uses a minimum of tubes to produce strong impulses simultaneously on a plurality of output conductors. It is to be noted that an increase in the number of output conductors does not cause any increase in the number of tubes required since all that need be added are additional output conductors and corresponding banks of keys for selectively coupling the output conductors to the various conductors 120, 131, 133, 135, 137, 139, 141, 143 and 145.

While the form of the invention shown and described herein is admirably adapted to fulfill the objects primarily stated, it is to be understood that it is not intended to confine the invention to the one form or embodiment disclosed herein, for it is susceptible of embodiment of various other forms.

What is claimed is:

1. In an impulse generator, the combination of a plurality of impulse-train-generating electronic devices, one of said devices being provided for each of the digits "9" through "1" and each of the devices having at least a pair of main electrodes and means to control conduction therebetween; a low-impedance operating potential supply circuit for each of said devices, the circuit for each device containing a low impedance in the circuit to one of the main electrodes, across which impedance a strong impulse is generated each time the device operates; means for supplying driving impulses to the conduction control means of the plurality of devices; control means coupled to the conduction control means of the devices for normally rendering each of the devices non-responsive to the driving impulses, said control means being operable to render the devices responsive to the number of driving impulses corresponding to the digit which it represents, whereby to produce, at said one of the main

electrodes of each device, an impulse train which contains the corresponding number of impulses; a plurality of separate output conductors; and means selectively coupling the output conductors to desired ones of said one main electrodes to enable the desired ones of said impulse trains to be impressed on the conductors, said low-impedance sources for the trains of impulses minimizing cross-talk between output conductors and also generating strong impulses whose quality is not impaired even when they are switched simultaneously to a plurality of output conductors.

2. An impulse generator as claimed in claim 1 in which the control means contains a plurality of gaseous electron tubes, one for each of the digits "1" through "9," each tube containing an anode, a cathode, and means to control conduction therebetween, an operating potential supply circuit for the tubes including an individual resistor in each cathode circuit, cathode-to-conduction control-means connections connecting the tubes in a chain beginning with the "9" tube whereby conduction in a tube can prime the next tube for operation, an input circuit connecting the conduction control means for the several tubes to the driving impulse generating means so that driving impulses will be applied to the tubes and fire the primed tubes one after another in succession, and means to prime the "9" tube; and in which the coupling between the control means and the impulse-training-generating devices includes connections from the cathodes of the tubes to the conduction control means of their related devices whereby the tubes, as they conduct, modify the control by the conduction control means and allow the impulse-train-generating devices to respond to the driving impulses.

3. An impulse generator as claimed in claim 2 in which the operating potential supply means for the tubes includes a device coupled to the impulse-train-generating device for the digit "1" and operated by the impulse of the "1" digit-representing train to modify the operating potential supplied to the tubes to thereby cause any conducting tubes in the control means to be extinguished.

4. An impulse generator as claimed in claim 1 in which the control means contains a plurality of electronic devices including a "start" device and a device for each of the digits "1" through "9," and circuits interconnecting the devices in an operative chain beginning with the "start" device and then the digit devices "9" through "1," said circuits enabling conduction in a device to prepare the next device for operation; in which the control means contains a circuit connecting the devices for the digits "9" through "1" to the means for supplying driving impulses, said impulses being effective to operate the devices which have been prepared for operation; in which the control means includes means to operate the "start" device to initiate the sequential operation of the other devices of the chain; in which the control means includes a resetting device which is operated by the impulse of the impulse train for the digit "1" to restore the devices of the chain to their inoperative condition; and in which the coupling between the control means and the impulse-train-generating devices includes connections between the devices of the chain corresponding to the various digits and conduction control means of the impulse train devices related to the same digits so that the device of the chain, when operated, can reduce the bias on the conduction control means of its re-

11

lated impulse-train-generating device and allow the driving impulses to be effective thereon.

5. In an impulse generator, the combination of a plurality of impulse-train-generating electronic devices, one of said devices being provided for each of the digits "9" through "1" and each of the devices having at least a pair of main electrodes and means to control conduction therebetween; a low-impedance operating potential supply circuit for each of said devices, each circuit containing a low impedance in series with one of the main electrodes of its related devices, across which impedance a strong impulse is generated each time the device conducts; means for supplying driving impulses to the conduction control means of the plurality of devices; control means coupled to the conduction control means of the devices and normally effective to render each of the devices non-responsive to said driving impulses; said control means, when operated, being effective to render each of the devices responsive to the number of driving impulses corresponding to the digit which it represents, whereby to produce an impulse-train at said one of the main electrodes which contains the corresponding number of impulses; means to cause the control means to operate; a plurality of denominational output conductors; a plurality of denominational means selectively coupling the output conductors to desired ones of said one main electrode to enable the impulse-trains containing the desired numbers of impulses to be impressed simultaneously on the conductors; and means operated by the impulse of the impulse-train for the digit "1" to restore the control means to its unoperated condition to prevent further impulses from being generated by the impulse-train generating devices.

6. In an impulse generator, the combination of a plurality of impulse-train generating devices, one of said devices for each of the digits "9" through "1" and each of the devices having at least a pair of main electrodes and means to control conduction therebetween; a low-impedance operating potential supply circuit for each of said devices, each circuit containing a low impedance in the circuit to one of the main electrodes of its related device, across which a strong output impulse is generated each time the device conducts; means for supplying driving impulses to the conduction control means of the plurality of devices; priming means coupled to the conduction control means of the devices and normally effective to render the impulses ineffective thereon, said priming means being operable from a normal condition to prime each of the devices in sequence to render the devices responsive to the number of driving impulses corresponding to the digit which it represents, whereby to produce, at said one of the main electrodes of each device, an impulse-train which contains the corresponding number of impulses; a "start" device coupled to the priming means, and, when operated, enabling the priming means to operate; a plurality of denominational output conductors; means selectively coupling the output conductors to desired ones of said one main electrode to enable the desired impulse trains selectively to be impressed on the conductors; and restoring means controlled from the impulse-train-generating device for the digit "1" and operable by the impulse representing the digit "1" for restoring the "start" device and the priming means to their unoperated condition.

7. In an impulse generator, the combination

12

of a plurality of impulse-train-generating electronic devices, one of said devices being provided for each of the digits "9" through "1"; an operating potential supply circuit for each of said devices, the circuit for each device containing a separate impedance, across which impedance an impulse is generated each time the device conducts; means for supplying driving impulses; means coupling the means for supplying driving impulses to the plurality of devices to supply driving impulses to the devices; control means coupled to the devices for normally rendering each of the devices non-responsive to the driving impulses, said control means, when operated, controlling the devices to render the devices responsive in succession and for a predetermined time so that each of the devices can respond to the number of driving impulses corresponding to the digit which it represents, whereby to enable each device to produce an impulse train which contains the corresponding number of impulses; means to operate the control means to render the devices responsive in succession; a plurality of separate output conductors; and means simultaneously coupling the output conductors selectively to desired ones of said devices to enable the impulse trains containing the desired numbers of impulses to be impressed on the conductors.

8. In an impulse generator, the combination of a plurality of impulse-train-generating electronic devices, one of said devices being provided for each of the digits "9" through "1"; an operating potential supply circuit for each of said devices, the circuit for each device containing a separate impedance, across which impedance an impulse is generated each time the device conducts; means for supplying driving impulses; means coupling the means for supplying driving impulses to the plurality of devices to supply driving impulses to the devices; control means connected to the means for supplying driving impulses to be operated by driving impulses and coupled to the devices, said control means normally effective to render the devices non-responsive to the driving impulses but, when driven by the driving impulses, operable to render each of the devices responsive in succession and for a predetermined time to enable each device to respond to the number of driving impulses corresponding to the digit which it represents, whereby to concomitantly produce impulse trains at the several devices which contain the corresponding numbers of impulses; means to initiate an operation of the control means by said driving impulses; a plurality of output conductors; and a plurality of output selector means for coupling the output conductors to desired ones of said devices to enable the impulse trains containing the desired numbers of impulses selectively to be impressed on the conductors.

9. In an impulse generator, the combination of a plurality of impulse-train-generating electronic devices, one of said devices being provided for each of the digits "9" through "1"; an operating potential supply circuit for each of said devices, the circuit for each device containing a separate impedance, across which impedance an impulse is generated each time the device conducts; means for supplying driving impulses; means coupling the means for supplying driving impulses to the plurality of devices to supply driving impulses to the devices; control means coupled to the devices and normally effective to

render each of the devices non-responsive to the driving impulses, said control means, when operated, controlling the devices to render each device responsive to the number of driving impulses corresponding to the digit which it represents, whereby to enable each device to produce an impulse train which contains the corresponding number of impulses; means coupling the control means to the means for supplying driving impulses to enable the control means to be operated by the driving impulses; a plurality of separate output conductors; and means selectively coupling the output conductors to desired ones of said devices to enable the impulse trains containing the desired numbers of impulses to be impressed on the conductors.

10. In an impulse generator, the combination of a plurality of impulse-train-generating electronic devices, one of said devices being provided for each of the digits "9" through "1"; an operating potential supply circuit for each of said devices, the circuit for each device containing an impedance, across which impedance an impulse is generated each time the device conducts; means for supplying driving impulses; means coupling the means for supplying driving impulses to the plurality of devices to supply driving impulses to the devices; control means coupled to the devices for normally rendering each of the devices non-responsive to the driving impulses, said control means, when operated, rendering each device responsive to the number of driving impulses corresponding to the digit which it represents, whereby the various devices operate concomitantly to produce impulse trains which contain the corresponding numbers of impulses; means connecting the control means to the means for supplying driving impulses to enable the control means to be operated by the driving impulses to render the devices responsive in sequence so that they can respond to the number of driving impulses corresponding to the digits which they represent; a plurality of separate output conductors; and means selectively coupling the output conductors to desired ones of said devices to enable the impulse trains containing the desired numbers of impulses to be simultaneously impressed on the conductors.

11. In an impulse generator, the combination of a plurality of impulse-train-generating electronic devices, one of said devices being provided for each of the digits of a notation and each of the devices having at least a pair of main electrodes and means to control conduction therebetween; an operating potential supply circuit for each of said devices, the circuit for each device containing an impedance in the circuit to one of the main electrodes, across which impedance a strong impulse is generated each time the related device conducts; means for supplying driving impulses; means coupling the means for supplying driving impulses to the conduction control means of the plurality of devices to supply driving impulses thereto; control means coupled to the conduction control means of the devices for normally rendering each of the devices non-responsive to the driving impulses, said control means, when operated, controlling the devices to render said devices responsive in succession to further impulses and for a predetermined time, 70 so that each device can respond to the number of impulses corresponding to the digit which it

represents, whereby to produce, at said one of the main electrodes of each device, an impulse train which contains the corresponding number of impulses; means coupling the control means to the means for supplying driving impulses to be operated by the driving impulses to render the devices responsive to the number of driving impulses corresponding to the digit which it represents; a plurality of separate output conductors; and means simultaneously coupling the output conductors selectively to desired ones of said one main electrode to enable impulse trains containing the desired numbers of impulses to be impressed on the conductors.

15. 12. In an impulse generator, the combination of a plurality of impulse-train-generating electronic tubes, one of said tubes being provided for each of the digits "9" through "1" and each of the tubes having at least a pair of main electrodes and means to control conduction therebetween; a low-impedance operating potential supply circuit for each of said tubes, the circuit for each tube containing a low impedance in series with one of the main electrodes of its related tube, 20 across which impedance a strong impulse is generated each time the tube conducts; means for supplying driving impulses; means coupling the conduction control means of the plurality of tubes to the means for supplying driving impulses to supply driving impulses thereto; control means connected to the means for supplying driving impulses to be operated thereby and coupled to the conduction control means of the tubes, said control means normally effective to render the tubes non-responsive to the impulses but, when driven by the impulses, operable to render each of the tubes responsive in succession to following driving impulses to enable each tube to respond to the number of driving impulses corresponding to the digit which it represents, whereby to produce an impulse train at said one of the main electrodes which contains the corresponding number of impulses; means to enable the control means to be driven by said driving impulses; a plurality of denominational output conductors; a plurality of denominational rows of keys selectively coupling the output conductors to desired ones of said one main electrode to enable the impulse trains containing the desired numbers of impulses selectively to be impressed on the conductors; and means operated by the impulse of the impulse train for the digit "1" to restore the control means to its unoperated condition to prevent further impulses from being generated by the impulse-train-generating tubes after the tubes have generated their corresponding numbers of impulses.

CARL F. RENCH.
